(57) **CLAIM**

The ornamental design for a carrier for spray delivery system as shown and described.

DESCRIPTION

FIG. 1 is a perspective view of an embodiment of a carrier for spray delivery system;

FIG. 2 is a front view of the carrier for spray delivery system shown in FIG. 1;

FIG. 3 is a rear view of the carrier for spray delivery system shown in FIG. 1 and opposite the front view shown in FIG. 2;

FIG. 4 is a side view of the carrier for spray delivery system shown in FIG. 1;

FIG. 5 is a side view of the carrier for spray delivery system shown in FIG. 1 and opposite the side view shown in FIG. 4;

FIG. 6 is a top view of the carrier for spray delivery system shown in FIG. 1; and,

FIG. 7 is a bottom view of the carrier for spray delivery system shown in FIG. 1 and opposite the top view shown in FIG. 6.

The dashed broken lines illustrate structure or features that form no part of the claimed design.

The dot-dash broken lines define the bounds of the claimed design and form no part thereof.

The grayscale shading illustrates contrasts in color and particular shades do not correspond to any particular color.

1 Claim, 7 Drawing Sheets
